R. H. MINICH.
CAR BRAKE.
APPLICATION FILED AUG. 24, 1917.

1,281,193.

Patented Oct. 8, 1918.

UNITED STATES PATENT OFFICE.

RUSSELL H. MINICH, OF PHILADELPHIA, PENNSYLVANIA.

CAR-BRAKE.

1,281,193.

Specification of Letters Patent. Patented Oct. 8, 1918.

Application filed August 24, 1917. Serial No. 137,928.

To all whom it may concern:

Be it known that I, RUSSELL H. MINICH, a citizen of the United States, residing at Philadelphia, in the county of Philadelphia and State of Pennsylvania, have invented new and useful Improvements in Car-Brakes, of which the following is a specification.

My invention relates to new and useful 10 improvements in car brakes, and more particularly to the brake operating mechanism, and has for its object to provide an exceedingly simple and effective device of this character which will be relatively inexpensive in the cost of manufacture, yet strong 15 and durable.

Another object of the invention is to provide a device of the character described, whereby the brake may be applied or released from the top, the end or the side of 20 the car.

A further object of the invention is to provide a simple and effective mechanism for retaining the brake handle or wheel in 25 any fixed position, after it has been moved, without the use of a ratchet wheel, a pawl, a dog or similar device.

A still further object of the invention is to provide an automatic sleeve ratchet or 30 dog, which requires no attention, and which does not have to be manually operated, the same being so arranged and situated as to prevent slipping of the brake mechanism should this be found necessary.

Further objects of the invention are to 35 save a trainman the time and trouble of climbing on the cars and to the top when only the brake is to be applied or released, to provide means whereby it is impossible 40 for a sudden release of the brake, causing what is sometimes termed "flying of the brake wheel" with its attendant injuries and death to the operators, and to provide a more effective application of the brake by 45 giving the operator greatly increased leverage in application, thereby making it possible for the operator to apply the brakes in a more powerful manner with only a fraction of the physical energy required with 50 brakes now in use.

With these ends in view, this invention consists in the details of construction and combination of elements hereinafter set forth and then specifically designated by the 55 claims.

In order that those skilled in the art to which this invention appertains, may understand how to make and use the same, I will describe its construction in detail, referring by numerals to the accompanying 60 drawing forming a part of this application, in which—

Figure 1, is a side elevation of my improved car brake operating mechanism, showing it applied to the end of a car. 65

Fig. 2, is an enlarged side elevation of the brake operating mechanism.

Fig. 3, is a front elevation thereof, illustrating the manner in which the brake is applied from the side of the car, portions 70 of this view being broken away and shown in section to clearly illustrate the construction.

Fig. 4, is a section at the line 4—4 of Fig. 3. 75

Fig. 5, is a bottom plan view thereof.

Fig. 6, is an enlarged detail sectional view of the ratchet pawl and its casing, and

Fig. 7, is an end view of the horizontal standard, showing the operating means attached thereto. 80

Fig. 8, is an enlarged side elevation of the stop disk carried by the threaded vertical shaft.

In carrying out my invention as here embodied 85 2 represents a car body having secured at one end and the bottom thereof a casing 3. This casing comprises a bracket or attaching member 4 of two right angled plates, the vertical plate 5 adapted to rest 90 against the end of the car body and the horizontal plate 6 adapted to underlie said car body.

With the attaching member is formed the integral forwardly projecting body 7 having a vertical bore 8 with which communicate opposite parallel vertical slots 9 running from the upper end of the body to a point adjacent the lower end thereof, and from the lower end of the body projects the 100 integral depending bracket 10, which also underlies the horizontal plate 6, and is formed integral therewith. The inner edge of the depending bracket is beveled or cut under as at 11, while the lower end is bifurcated to form the arms 12 between which is arranged the grooved pulley 13, the same being journaled upon a shaft 14, the ends of the latter being mounted in the arms 12. In the bore 8 of the body is slidably mount- 110

ed a sleeve 15 internally threaded as at 16, and from this sleeve in opposite directions project a pair of integral lugs 17 arranged to work in the slots 9, and the ends of these 5 lugs project beyond the outer walls of the casing. In this bore 8 is also mounted a vertical shaft 18 threaded externally as at 19, and these threads engage the internal threads of the sleeve 15 to cause the latter to ascend or descend in the bore 8. The lower end of the sleeve 15 is spiral in shape, thereby forming a shoulder which when the sleeve is at its lowermost position is adapted to engage the shoulder 20 produced by 10 the spiral shape of the upper end of the disk 21, said disk being attached to the lower end of the shaft 18 in any suitable manner as by a pin 22, and the lower surface of this disk is convex and is adapted to rest 15 upon the convex upper surface of the bearing disk 23 situated at the bottom of the bore 8. On the outwardly projecting ends of the lugs 17 are pivoted the side bars 24, the same being held in place by nuts 25 20 threaded on said lugs and these side bars are of sufficient length to reach beyond the bevel or undercut surface 11 of the bracket 10 and the outer circumference of the grooved pulley 13.

25 Between the outer ends of these side bars 24 is pivotally mounted the clevis 26, the same being held in place by nuts 27 threaded on the projections 28 which pass through the side bars 24. This clevis is also provided with a hole 29 whereby a chain 30, forming a part of the brake rigging 31, may be attached to the clevis.

30 On top of the body 7 is secured a cap 32 through which projects the upper end of the shaft 18 and abutting this upper end of the shaft is the lower end of the alined standard 33, the same being properly positioned by the guide 34 carried by and projecting from the upper edge of the vertical plate 5.

35 When in use the standard may be supported by additional guide brackets attached to the car body and the upper end of the standard carries an operating means such as a wheel 35.

40 A sleeve ratchet 36 is slidably mounted upon the shaft 18 and standard 33 in the region of their meeting ends, so as to overlap a small portion of each. The upper edge of 45 their sleeve ratchet is provided with ratchet teeth 37, while in the side walls adjacent the upper end are formed diagonal slots 38, and adjacent the lower end are formed vertical slots 39, the latter running entirely 50 to the bottom of the sleeve for convenience of assembling the parts.

55 The sleeve ratchet is attached to the standard by a pin 40 passing through the standard, and projecting into the diagonal slots 38, while said sleeve is attached to the

shaft 18 by another pin 41 passing through said shaft, and projecting into the vertical slots 39.

Above the upper edge of the sleeve ratchet and the path of upward travel of said sleeve 70 is arranged a ratchet dog or pawl 42, the nose of which is adapted to coöperate with the teeth of the sleeve ratchet under certain conditions. The ratchet dog or pawl 42 is pivoted as at 43 within a pawl or dog casting 44, the latter being provided with a shoulder 45 to act as a stop for limiting the downward movement of the dog or pawl when the lip or projection 46 of the pawl engages said shoulder. The pawl casting 80 is attached to the vertical plate 5 as by a threaded trunnion 47.

The standard 33 has mounted thereon a bevel gear 48 with which meshes a bevel gear 49 mounted on the inner end of a horizontal standard 50, said horizontal standard projecting in any desirable direction either endwise or sidewise, as here shown, and on the outer end of said standard 50 is mounted a suitable operating means, such as a wheel 90 or handle.

In the present instance, I have shown an operating means or crank handle of unique construction, in which the horizontal standard 50 is provided with a squared outer end 95 51 and on the circular portion of said standard adjacent the squared end is revolubly mounted the arm 52, provided with integral guides, 53 projecting from one face of the arm, and in these guides is slidably mounted 100 the wrench or locking member 54, provided with a socket 55, arranged to register with the squared end 51 of the horizontal standard.

The wrench or locking member 54 is actuated by a handle 56 pivoted to the outer end of the arm 52 and provided with a lug or projection 57, whereby said handle is pivoted to the lower end of the lock member 54. The operating means is held in its 110 proper position upon the horizontal standard 50 by means of suitable rings, washers or collars 58, securely attached to the standard in some suitable manner as by pins 59.

In practice the vertical standard 33 and 115 the threaded shaft 18 may be formed of one piece to produce an operating spindle and the sleeve ratchet and pawl eliminated as these latter parts are required only where an extraordinary guard against the release 120 of the brakes is insisted upon.

The operation of the device is as follows:—

125 By turning the standard 33 in the proper direction to cause the internally threaded sleeve 15 to ascend in the bore 8, the upward movement of said sleeve will cause the side bars 24 to fulcrum upon the corners of the attaching member 4 or upon suitable fulcrum blocks 60 projecting forwardly 130

from the attaching member 4 and sidewise from the body 7, said fulcrum blocks being formed integral with these parts.

The upward movement of the internally threaded sleeve will raise the outer ends of the side bars 24 and because of the engagement of said side bars with the fulcrum blocks above referred to, the inner or free ends of said side bars will move downward thereby shortening the distance between the clevis 26 and the brake hanger, so as to firmly draw the brake against the wheels.

When the sleeve 15 has been raised a certain distance, the inner or free ends of said side bars 24 will be moved around, so as to carry the clevis beneath the groove wheel or pulley 13, at which time the chain 30 will be caused to engage said groove pulley and any further upward movement of the sleeve 15 will cause the brake to be applied as effectively as desired.

The above specified action is obtained either by revolving the standard 33 or by raising the handle 56 until it lies at right angles, and the arm 52 will cause the socket 55 of the wrench or locking member 54 to register with the squared portion 51 of the standard 50, after which the operating device may be revolved as will be obvious, so as to revolve the horizontal standard and transfer the motion and power therefrom through the bevel gears 49 and 48 to the vertical standard 33.

When the locking member 54 is out of engagement with the squared portion 51 of the horizontal standard 50, the operating device will hang downward since the weight of the locking member 54 and the handle 56 will move said locking member to its operative position, and the weight of the entire device will cause the same to hang downward in a virtually vertical position as shown, permitting the horizontal standard to freely revolve.

Where the sleeve ratchet is used to prevent retrograde movement of the brake rigging, said sleeve 36 is situated in the region of the meeting ends of the standard 33, and the threaded shaft 18, so that when the standard 33 is revolved in the direction for causing the sleeve 15 to ascend, the ends of the pin 40 will travel in the diagonal slots 38, causing the sleeve ratchet 36 to rise until the teeth 37 engage the pawl 42, and when the teeth of this sleeve ratchet are in engagement with the pawl, the ends of the pin 40 will have traveled to the lower ends of the diagonal slots, causing the sleeve ratchet 36 to revolve with the standard 33 and carry the threaded shaft 18 with it. Since the ends of the pin 41 are in engagement with the walls of the slots 39, any further revolving of the standard 33 will cause the pawl 42 to ride over the teeth, and when the desired adjustment of the internally

threaded sleeve 15 and therefore the brake rigging has been obtained, the brake cannot be accidentally released, as this action upon the side bars 24 will cause the sleeve 36 to be disengaged from the pawl 32, but when it is desired to release the brakes, it is only necessary to reverse the movement of the standard 33, which will move the ends of the pin 40 to the opposite ends of the diagonal slots 38, causing the sleeve ratchet 36 to be forced downward for disengaging the teeth thereof from the pawl 42, after which the continued revolving of the standard 33 will release the brakes.

It is to be noted that after the sleeve 36 has been moved downward, a certain distance, the lip 46 of the pawl 42 will engage the stop shoulder 45 of its casing and permit the teeth to move out of engagement with the nose of said pawl.

Of course, I do not wish to be limited to the exact details of construction as herein shown, as these may be varied within the limits of the appended claims without departing from the spirit of my invention.

Having thus fully described my invention, what I claim as new and useful, is:—

1. A car brake operating mechanism, a casing having a vertical bore, and oppositely disposed parallel slots communicating with said bore, an internally threaded sleeve slidably mounted within said bore, lugs carried by said sleeve and projecting through the slots in the casing, a threaded operating means projecting into the bore and engaging the threaded sleeve, whereby the revolving of said operating means will raise or lower the sleeve, side bars pivoted to the lugs and adapted to fulcrum upon portions of the casing, and a clevis carried by the outer ends of said side bars and adapted to connect with the brake rigging of a car.

2. In a car brake mechanism the combination with a car and the brake rigging thereof, of a casing secured to the car, said casing consisting of an attaching member of two plates at right angles to each other, a body having a vertical bore and vertical parallel oppositely disposed slots communicating with said bore, a depending bracket having an undercut surface and bifurcated at its lower end to place a pair of parallel arms, and fulcrum blocks projecting forwardly from the lower portion of the attaching member and sidewise from the body, a shaft mounted between the arms and the bifurcated end of the depending bracket, a grooved pulley journaled on said shaft, an internally threaded sleeve slidably mounted in the bore of the body, lugs carried by said sleeve, and projecting through the slots in said body, a threaded operating means arranged in said bore and cooperating with the threaded sleeve to raise or lower the same, side bars pivoted to the lugs and

- adapted to fulcrum upon the fulcrum blocks as the threaded sleeve is raised, and means for connecting the inner or free ends of said side bars with the brake rigging.
5. In a car brake mechanism the combination with a car and the brake rigging thereof, of a casing secured to the car, said casing consisting of an attaching member of two plates at right angles to each other, a body 10 having a vertical bore and vertical parallel oppositely disposed slots communicating with said bore, a depending bracket having an undercut surface and bifurcated at its lower end to place a pair of parallel arms, and fulcrum blocks projecting forwardly from the lower portion of the attaching member and sidewise from the body, a shaft mounted between the arms and the bifurcated end of the depending bracket, a 15 grooved pulley journaled on said shaft, an internally threaded sleeve slidably mounted in the bore of the body, lugs carried by said sleeve, and projecting through the slots in said body, a threaded operating means arranged in said bore and coöperating with the threaded sleeve to raise or lower the same, side bars pivoted to the lugs and adapted to fulcrum upon the fulcrum blocks as the threaded sleeve is raised, means for 20 connecting the inner or free ends of said side bars with the brake rigging, a cap attached to the top of the body through which projects the operating means, and a guide for said operating means secured to the 25 upper ends of the attaching member.
4. In a car brake mechanism the combination with a car and the brake rigging thereof, of a casing secured to the car, said casing consisting of an attaching member of two 30 plates at right angles to each other, a body having a vertical bore and vertical parallel oppositely disposed slots communicating with said bore, a depending bracket having an undercut surface and bifurcated at its lower end to place a pair of parallel arms, and fulcrum blocks projecting forwardly from the lower portion of the attaching 35 member and sidewise from the body, a shaft mounted between the arms and the bifurcated end of the depending bracket, a grooved pulley journaled on said shaft, an internally threaded sleeve slidably mounted in the bore of the body, lugs carried by said sleeve and projecting through the slots in said body, a threaded vertical shaft arranged in the bore and engaging the threaded sleeve to raise or lower the same, a cap secured to 40 the top of the body and through which projects the upper end of the threaded shaft, a standard, the lower end thereof abutting the upper end of the threaded shaft in alinement therewith, a guide for guiding said standard 45 secured to the upper end of the attaching member, a sleeve ratchet having its upper end serrated, provided with diagonal slots adjacent its upper end, said sleeve being mounted upon the threaded shaft and standard in the region of their meeting ends, a pin passing through the lower end of the standard and projecting into the diagonal slots, another pin passing through the upper 50 end of the threaded shaft with its ends projecting into the vertical slots, a pawl pivoted within said casing provided with a lip adapted to engage the stop shoulder for limiting the downward movement of the pawl, the nose of said pawl being so situated as to be in the path of upward travel of the sleeve ratchet, side bars pivoted to the lugs of the threaded sleeve and adapted to fulcrum 55 upon the fulcrum blocks when the threaded sleeve is raised, means for connecting said side bars with the brake rigging, a beveled gear on the standard, a horizontal standard, having a squared outer end, a beveled gear 60
- adjacent its upper end, said sleeve being mounted upon the threaded shaft and standard in the region of their meeting ends, a pin passing through the lower end of the standard and projecting into the diagonal 70 slots, another pin passing through the upper end of the threaded shaft with its ends projecting into the vertical slots, a pivoted pawl arranged in the path of upward travel of the sleeve ratchet, a pair of side bars pivoted to 75 the lugs of the threaded sleeve, and means for connecting said side bars with the brake rigging.
5. In a car brake mechanism the combination with a car and the brake rigging thereof, of a casing secured to the car, said casing consisting of an attaching member of two plates at right angles to each other, a body having a vertical bore and vertical parallel oppositely disposed slots communicating 80 with said bore, a depending bracket having an undercut surface and bifurcated at its lower end to place a pair of parallel arms and fulcrum blocks projecting forwardly from the lower portion of the attaching 85 member and sidewise from the body, a shaft mounted between the arms and the bifurcated end of the depending bracket, a grooved pulley journaled on said shaft, an internally threaded sleeve slidably mounted in the bore of the body, lugs carried by said 90 sleeve and projecting through the slots in said body, a threaded vertical shaft arranged in the bore and engaging the threaded sleeve to raise or lower the same, a cap secured to 95 the top of the body and through which projects the upper end of the threaded shaft, a standard, the lower end thereof abutting the upper end of the threaded shaft in alinement therewith, a guide for guiding said standard 100 secured to the upper end of the attaching member, a sleeve ratchet having its upper end serrated, provided with diagonal slots adjacent its upper end, said sleeve being mounted upon the threaded shaft and standard in the region of their meeting ends, a pin passing through the lower end of the standard and projecting into the diagonal slots, another pin passing through the upper 105 end of the threaded shaft with its ends projecting into the vertical slots, a pawl pivoted within said casing provided with a lip adapted to engage the stop shoulder for limiting the downward movement of the pawl, the nose of said pawl being so situated as to be in the path of upward travel of the sleeve ratchet, side bars pivoted to the lugs of the threaded sleeve and adapted to fulcrum 110 upon the fulcrum blocks when the threaded sleeve is raised, means for connecting said side bars with the brake rigging, a beveled gear on the standard, a horizontal standard, having a squared outer end, a beveled gear 115

on the inner end of said horizontal standard meshing with the first named gear, an arm revolubly mounted on the horizontal standard in proximity to the squared end, integral 5 guides, formed with said arm, and projecting from one face thereof, a locking member slidably mounted in said guides, said locking member provided with a socket adapted to register with the squared end of the horizontal 10 standard, a handle pivoted to the outer end of the arm and provided with a lug for pivotal connection with the outer end of the locking member, whereby the movement of said handle to a position at right 15 angles to the arm, will cause the locking member to engage the squared end of the horizontal standard, so as to lock the parts together and means mounted upon the horizontal standard for holding the arm and locking member in other proper positions.

6. In a device of the character stated, a standard having a round portion and a squared end, an arm revolubly mounted on the round portion of the standard, adjacent 20 the square end, guides carried by the arm and projecting from one face thereof, a locking member provided with a socket slidably mounted in the guides, the socket of said

locking member being adapted to register with the square end of the standard to prevent the rotation of the arm independently of said standard, collars on said standard for positioning the arm and locking member, a handle pivoted to the outer end of the arm and a lug projecting from said handle for pivotal connection with the locking member whereby the movement of said handle to a position at right angles to the arm will cause the locking member to engage the squared end of the standard. 40

7. In a device of the character stated a revolving threaded member, a revolving sleeve adapted to be actuated by said revolving member, the lower edge of said sleeve being cut spirally to form a shoulder, a disk having 45 its upper edge cut spirally to form a shoulder, said disk being pinned to the end of the revolving member, the shoulder of the sleeve adapted to engage the shoulder on the disk when at its lowermost position to prevent 50 the jamming of said sleeve on the revolving member.

In testimony whereof, I have hereunto affixed my signature.

RUSSELL H. MINICH.
